BOTTLE CLOSURE

Samuel C. Miller, Louisville, Ky., assignor to
Frankfort Distilleries, Incorporated, Louisville,
Ky., a corporation of West Virginia

Application September 21, 1942, Serial No. 459,147

4 Claims. (Cl. 215—52)

The present invention relates to improvements in bottle closures and more specifically resides in the substitute stopper for Coca Cola or like bottles; or in other words a stopper to replace the present crown cork.

An object of the invention is to dispense with the use of metal in the construction of bottle stoppers, and at the same time to produce a substitute stopper of a different material of greater present availability and without sacrificing any of the advantages of the composite cork and metal crowned and crimped stoppers.

A further object of the invention resides in providing an improved bottle stopper which may be sold apart from the bottles as an independent assembly, and so constructed and arranged as to permit of easy and prompt application to a sealing position in the mouth of the bottle.

A still further object of the invention is to provide an improved stopper for bottles and the like in which the internal gas pressure will react to tighten rather than disturb the seal produced by the stopper.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a perspective view of an improved bottle stopper constructed in accordance with the present invention and shown in an assembled condition independently of the bottle.

Figure 2 is a bottom plan view of the same.

Figure 3 is a longitudinal section taken through the improved stopper on the line 3—3 of Figure 1.

Figure 4 is a vertical section taken through the improved stopper and a portion of a bottle neck showing the initial phase of application.

Figure 5 is a similar view showing a subsequent position of the glass marble or ball.

Figure 6 shows the final position of the marble or ball and the sealed condition.

Figure 7 is a similar view showing the method of release of the stopper.

Figures 8, 9 and 10 are all vertical sections showing a modified form of stopper with the ball in successive phases of position.

Referring more particularly to the drawing 10 designates the neck of a form of bottle well known upon the market as that in which Coca Cola and other beverages are widely distributed and sold. Such bottles have for some time been

successfully closed by what is known as a crown cork in which the corrugated flange of the metal of the stopper is crimped under a lip or shoulder 11 to compress the cork disc tightly upon the mouth of the bottle neck. It is the purpose of the invention to form below the mouth of the bottle an internally enlarged portion 12 between an upper constricted zone 13 and a lower constricted zone 14. The enlarged portion 12 is blown in the bottle and forms an external bulge to maintain uniformity of thickness of wall and to eliminate weakened areas. The internal wall of the enlarged portion 12 is preferably globular or formed on the section of a sphere.

15 The improved stopper which may be made of wood or some other appropriate material is comprised of a head 15 and a shank 16. The head is larger than the shank producing a shoulder 17 to rest on the lip or mouth of the bottle and to arrest the downward movement of the stopper. In the head and shank are communicating passages 18 and 19 with a shoulder 20 between the same formed by the differential diameters; the diameter of the upper passage 18 being greater than that of the shank passage 19. These passages conjointly form a continuous bore through the stopper opening through the head 15 and through the shank 16. The shank 16 is preferably thinner of wall than the head 15 and is of an expandable material. A glass marble or ball 21 of a diameter slightly in excess of the diameter of passage 18 is adapted to be forced downwardly into the passage 18 and ultimately into the passage 19 and constitutes with the wall of the shank 16 a sealing stopper for the bottle.

40 The diameter of the ball 21 will be such as to expand the wall of the shank 16 tightly out against the internal globular wall of the enlarged portion 12, the diameter of the ball 21 corresponding to the curvature of wall portion 12 with allowances made for the intervening thickness of wall of shank 16.

The method of use is as follows:

45 The wood shell fits loosely in the bottle. The top flange or head 15 acts to keep the wood shell from being forced into the bottle neck. The wall of shank 16 fits loosely in the bottle around the inside top. The glass marble 21, when forced into the shell, expands the same and it also expands the wall of shank 16.

50 The condition of the parts is initially shown in Figures 1 to 4 inclusive in which the glass marble 21 initially resides in the passage 18, being frictionally held therein by the wedging

action of the ball upon the wood wall and the reaction of the elasticity inherent in the wood about the ball. This friction effect will retain the ball in the head 15 during its transportation and sale and until its use is required. When applying the stopper it is first put into position illustrated in Figure 4. Then it is forced down by the fingers or by an appropriate implement inserted through the top of passage 18. Figure 5 shows the position of the ball opposite the constricted zone 13.

Figure 6 shows the final position of the ball 21 lying wholly within the enlarged globular portion 12 and expanding the wall of shank 16 out against the wall 12. This constitutes the resting place of the glass marble and the constricted zone 14 below will prevent the marble from easily falling by gravity through the shank passage 19. When inside gas pressure has a tendency to force the stopper out, the upward movement wedges the shell cork against the top constriction 13. The greater the pressure, the tighter the cork.

To open the bottle, the marble 21 is pushed downwardly, as indicated in Figure 7, falling inside the bottle. The shell may then be lifted out and removed, after which the glass marble 21 will leave the bottle along with the contents.

By forming the passages 18 and 19 of differential diameters, with the shell larger at the top and smaller at the bottom, expansion of the shell will be greater under the spreading influence of the ball as it is pushed downward past the improved constriction 13 of the bottle neck. The vertically deep head 15 permits the ball to be first pressed into the opening 18 by way of assembly before the shell is placed in the bottle neck. The flange or head 15 is therefore of sufficient vertical depth to form a housing for the ball 21 or at least to afford sufficient wide wall area of contact with the ball to frictionally hold the same in place.

Referring more particularly to Figures 8, 9 and 10 passages may be provided but preferably the two passages constituting the hole through the stopper are reduced in size at a point corresponding to the greatest bulge in the upper part of the bottle neck. The reduction in size or diameter is indicated by the shoulder portions 22 and 23; that is the internal diameter of the hole is reduced throughout an area included between these points 22 and 23. The reduced size of the hole should not extend over one-fourth of an inch from top to bottom with the center, as stated above, opposite the greatest extent of the bottle. Stoppers in accordance with this construction have actually been made and proved tight.

A stopper of this character drops into the bottle neck easily. Glass ball which goes into the hole of the stopper drops in the hole easily and comes to rest on top of the inside collar 22 of the shell stopper. A plunger is used to force the glass ball 21 past the upper part of the shoulder 22 until the ball comes to rest inside such shoulder 22, that is within the internally thickened or reduced section 22, 23 of the shell shank. This condition is illustrated in Figure 9. The thickness of this shoulder or area is about one-sixty-fourth of an inch.

To open the bottle, the ball is pushed completely past, that is below, the lower shoulder 23 and into the inside of the bottle, as illustrated in Figure 10.

It is obvious that various changes and modifications may be made in the details of con-

struction and design of the above specifically described embodiment of this invention without departing from the spirit thereof, such changes and modifications being restricted only by the scope of the following claims.

What is claimed is:

1. An improved bottle stopper for use with a bottle having a restricted mouth comprising an integral head and shank having through communicating passages, the diameter of the head passage being greater than that of the shank passage, a shoulder formed internally between said passages, said head being of a greater width than the shank to rest upon the mouth of the bottle while the shank fits loosely within the mouth of the bottle, and a ball insertible through said passages and being of a diameter greater than that of either passage, said head passage being of sufficient depth and width to initially accommodate the ball in the original assembly of the parts, said head and shank being of relatively expansible material, said communicating passages opening at the lower shank end into the interior of the bottle, said ball being unitary, self-contained and free to be pushed downwardly through the shank and into the bottle.

2. For use with a bottle having an internally enlarged portion between constrictions, an improved stopper comprising a head of a width to fit upon the mouth of the bottle and expansible shank to fit loosely within the mouth of the bottle and across said constrictions and enlarged portion, said head and shank having axially aligned passages therethrough, and a globular member insertible through said head and shank passages for expanding the shank into the said enlarged portion in sealing relationship to the bottle neck, said passages opening at the inner end of said shank directly into the bottle, said globular member being a free, self-contained and unitary member adapted to be pushed through the inner end of said shank into the container to free the stopper from the bottle.

3. A bottle stopper for use with a bottle having a mouth and a neck portion having an enlarged internal portion separating two constricted portions, comprising an integral head and shank of expansible material having axially aligned communicating passages therethrough, said shank being disposed across said enlarged portion of the neck of the bottle when the stopper rests in the mouth thereof, a ball insertible through said passages and having a diameter greater than either of said passages to expand said shank into sealing relationship with the neck of the bottle at the enlarged internal portion thereof, said passages opening through the inner end of said shank directly into the interior of the bottle, said ball being an unattached ball capable of rotation on axes angularly disposed to one another and removable from the shank into the interior of the bottle through the opening in the inner end of said shank.

4. In combination with a container having a mouth formed with internally constricted portions at opposite sides of an internally enlarged part globular section, an improved stopper comprising a head and a shank with an external shoulder between the same for resting upon the mouth of the container, said head and shank both being of expansible material and having registering passages opening through the upper face of the head and through the inner end of the shank, said shank being sufficiently

long to span the space between both said constricted portions and the globular section of the container neck, the internal wall of said shank having a shouldered portion, said internal shank wall also having a thickened portion opposite said globular section, and a free and unattached ball insertible initially into the passage in said head and being of slightly greater diameter than said passage to frictionally bind in said head, said head being sufficiently deep to 10

initially accommodate said ball, said ball movable downwardly and into said shank to expand the thickened wall portion of said shank outwardly into the globular section of the container mouth, said ball adapted to be pushed all the way inwardly through said shank and into the bottle in the act of freeing the stopper from such bottle.
